UNITED STATES PATENT OFFICE

WALTER DORWIN TEAGUE, OF FOREST HILLS, NEW YORK, ASSIGNOR TO TAYLOR INSTRUMENT COMPANIES, OF ROCHESTER, NEW YORK, A CORPORATION OF NEW YORK

DESIGN FOR A RECORDER CASE

Application filed October 21, 1931. Serial No. 41,479. Term of patent 14 years.

To all whom it may concern:

Be it known that I, WALTER DORWIN TEAGUE, a citizen of the United States of America, residing at Forest Hills, county of Queens, State of New York, have invented a new, original, and ornamental Design for a Recorder Case, of which the following is a specification, reference being had to the accompanying drawings, wherein:

Fig. 1 is a front view of the article showing my new design.

Fig. 2 is a side view thereof.

I claim:

The ornamental design for a recorder case, as shown.

WALTER DORWIN TEAGUE.
